LIQUID CONTAINER WITH DISPENSING DEVICE

Christoph Karageorgieff, 5, Wolfersberggasse,
Vienna XIV, Austria

Filed Nov. 9, 1959, Ser. No. 851,895

10 Claims. (Cl. 222—483)

This invention relates to a dispensing device on liquid containers, which device has a single filling, dispensing and cleaning opening which in the dispensing position is at the lower end of the container and which is provided with a screw closure, into which a housing flange with dispensing means, which can be separately pulled out, and an air inlet device which opens in response to subatmospheric pressure in the container, can be tightly and non-rotatably inserted so that it can be locked and closed.

For a container closure a closure member has already been disclosed which is screwed into a screw-threaded ring of the container and which has a dispensing device for the direct outflow of the contents of the container as well as an air inlet valve. However, the dispensing device is not arranged to be pulled out and does not have a spring-loaded return valve so that liquid can be filled into a container through the dispensing valve. The effective elements (lips) of the air inlet are accessible from the outside with any pin so that air inlet valve can be opened during refilling.

Moreover, a dispensing cock is known with which a spring-loaded return valve is associated, which is removably affixed on the outlet side with a removable cap nut whereas the dispensing cock does not have an air inlet opening directly associated with it.

The dispensing device for liquids according to the invention has the purpose of preventing a refilling of the container through the dispensing device so that liquid cannot be filled into the container through the single container opening unless the sealed screw closure is opened which contains the dispensing device. This prevents the filling of inferior products into the container which is provided with a trade mark, the sign of a firm or the like, and the sale of such inferior products as a high-quality product.

In order to achieve the object stated the air inlet device is connected according to the invention to a separate conduit of the housing flange, the valve member of the air inlet means is controlled by a diaphragm of a diaphragm housing arranged in the container and the dispensing means provided in a manner known per se in a slide cylinder which can be pulled out has associated with it on the side facing the container a spring-loaded check valve which opens automatically in response to superatmospheric pressure in the container and which is inaccessible from the outside.

It is known from experience that the inflowing air needs only a fraction of the cross-section required for the outflow of a liquid, particularly of thick oils. For this reason an exchange of liquid and air through a common duct requires a cross-section which is excessively large for the exchange of air and the control of which by the associated valve means involves difficulties as far as the exchange of air is concerned. This is remedied by the provision of a plurality of conduits according to the invention to enable one valve member to be adapted to its purpose of controlling an air conduit small in diameter

2

independently of the design of the valve means in the liquid conduit.

The drawings show an illustrative embodiment of the subject matter of the invention. Fig. 1 is a longitudinal sectional view showing a dispensing device in inserted position. Fig. 2 shows the same in dispensing position, Fig. 3 is a view partly in side elevation and partly in cross-section showing the air pressure control valve (air inlet device) according to Fig. 1 in upright position and Fig. 4 shows the locking segment of Fig. 1 in inserted position in a side elevation associated with Fig. 6. Fig. 5 shows the device in locking position. Fig. 6 is a rear view showing the inserted position without air pressure control valve. Fig. 7 is a sectional top plan view showing the screw ring. Fig. 8 is a front view showing the housing flange. Fig. 9 is a front view showing the slide cylinder with the cock plug in closed position, shown in section, and Figs. 10 and 11 show details of the locking means.

In Figs. 1, 2, 1 is the shell and 2 the end of a barrel, which has no openings with the exception of a screw-threaded ring 3, which is welded into the end 2 which is at the bottom in the dispensing position shown. Through this ring the barrel can easily be cleaned and filled.

The screw-threaded ring 3 has inserted therein a sealing ring 4, in which a housing flange 5 is tightly screwed by means of a screw ring 7. The housing flange 5 has a socket 6 which extends into the barrel and together with the stops 8 (Figs. 1, 6) provided at the screw-threaded ring holds the flange 5 against rotation. The screw ring 7 has two claws 9, 9' for the application of a wrench.

Slidably mounted in the housing flange 5 is the slide cylinder 10, which is held against rotation by a groove 11 and a screw 12 (Figs. 2, 8 and 9). The stop preventing the removal of the cylinder 10 is formed by a cylinder head 13, 13', which is flattened at its top at 14 to provide space for the socket 6. In the front part of the cylinder 10 a cock plug 15 is incorporated. The opening 16 of this plug together with an opening 17 in the cylinder form an angle cock. The opening 17 forms at the same time the discharge mouth (Figs. 1, 2 and 9).

The plug 15 has a sealing rim 18, which extends beyond the periphery of the cylinder. When the cylinder is inserted this rim engages a gasket 20 inserted in a groove 19 of the housing flange 5. This will provide a seal against any leaks between the cylinder 10 and the housing flange 5 as well as between the cylinder 10 and the cock plug 15. The groove 19 and the gasket 20 extend below the screw-threaded ring 7, so that the gasket 20 is retained in position by this ring.

In the axis of the plug a bipartite spindle 21, 21' is arranged, the front part 21 of which is of reduced diameter in the plug 21 and is held against rotation by the groove and nose 22 (Figs. 1 and 11) and as a screw bolt is firmly and tightly screwed by the spindle nut part 21' to the plug with the aid of a sealing ring and is secured by a pin 23. The two parts of the cylinder head 13, 13' have beads and are tightly connected by means of the bolts and nuts 24. Part 13' is formed as a valve seat 25 and has a stirrup bearing 26 providing an abutment for the spindle 21'. That end of the spindle which projects into the barrel has affixed thereto a slotted hub 27 by means of a clamp screw 28 to prevent the removal of the spindle and the plug 15.

The hub 27 carries an arm 29, which carries a segment 30, to one end of which a strong leaf spring 31 formed like the segment is, e.g., riveted (32). This spring tends to spring somewhat away from the other end of the segment (Fig. 4). The segment and the hub 27 are so adjusted relative to the cock plug that when the cock is

closed (Fig. 6) the segment 30 with the stop 33 limits the rotation of the cock 15 in the closing sense and at the same time the spring 31 snaps in at a rib 26' with which the bearing stirrup 26 is affixed to the cylinder head 13' (Fig. 1). Thereby the plug is locked. The plug cannot be turned open until the slide cylinder 10 has been sufficiently pulled out (Fig. 2) so that the end of spring 31 snapped in at 26' is urged back from a projection 35 at the socket 6 and is thus lifted from the rib 26' to remove the lock. The socket 6 has a recess 34 (Figs. 1 and 2) so that a web portion 6' remains at the end of the T-shaped socket. The projection 35 protrudes towards this web portion to the full width of the flange (Fig. 6). After the plug has been turned open in the clockwise sense when seen from the rear as in Fig. 6, the segment 30 and the spring 31 enter this recess to prevent the slide cylinder 10 from sliding into the housing flange 5 before the mouth of the plug opens. The rotation of the plug to the fully open position is limited by the stop 33.

The spindle 21 extends outwardly and forms a head 21'. This spindle portion carries a handle consisting of a plate 37 with handle wings 39, 39' and the knob 38. These parts have a bore which accommodates the spindle head 21'. The spindle 21 is guided in a step formed at 40 in this bore. The step 40 (Fig. 10) has recesses 41 for receiving a pin 42. A coil spring 43 (Fig. 1) tends always to urge the handle outwardly. If the handle is turned until the recesses 41 are in registry with the pin 42 the pin snaps into the recesses as far as the spindle head 21' and couples the handle to the spindle. This causes the cock plug 15 to be coupled to the segment 30 so that the plug 15 can be operated by the handle within the segment stops 33, 33' when the sliding cylinder has been pulled out.

Two bolts 44 are also pivoted to the cock plug 15 by means of two pins 45 (Figs. 1, 11). These bolts have at their opposite ends pins 46, which engage grooves 47 extending spirally in the plate 37 (Fig. 10) of the handle. The pins 45 and 46 are so long that the bolts cannot fall out even if the handle is coupled to the pin 42 as described hereinbefore so that the handle snaps slightly out. On the other hand the bolts are still free to move when the handle is forced inwardly (Fig. 1) and thus disengages the pin 42 so that the handle can be rotated independently of the pin and can be supported against the same. The rotation of the handle relative to the spindle 21 and the pin 42 and consequently relative to the cock plug 15 causes the cam grooves 47 to rotate the bolts 44 outwardly or inwardly, depending on the direction of rotation. The angle of rotation is finally limited by the engagement of the pins 46 in the grooves 47. As has already been mentioned the cylinder can only be pushed into the housing flange 5 if the cock is closed. When the handle is coupled with the spindle the handle can only be turned to close as far as to the stop 33 in the arrangement shown in Fig. 6. The spring 43, however, is so strong that the handle cannot be pushed in to become uncoupled unless the cylinder has been fully pushed in and the sealing rim 18 engages the seal 20. In this position the segment 30 together with the spindle 21 has been held against rotation after the spring 31 has left the recess 34. Now the handle can only be rotated when it has been pushed in to become uncoupled. In this position the handle is locked by the bolt pins 46 which engage toward the left when the bolt has been turned inwardly. For this reason the handle can be turned only to the right whereby the bolts are turned outwardly. This end position is shown in Figs. 10, 11. The screw ring 7 has a rim 48, the inside surface 49 of which has a conical taper (Fig. 7). This conical surface is engaged by the emerging bolts 44, which are cammed thereby to urge the entire piston system into engagement. Thereby the sealing rim 18 is tightly forced against the gasket 20. The wing 39' disposed next to the claw 9' in this locked

position has a bore 50 and the claw 9' has a transverse bore 51 for a seal cord 52 (Fig. 5).

Following the opposite sequence, dispensing is possible only if the seal has been removed and the handle is unlocked by turning it to the left until it is coupled to the spindle 21, 42, whereafter the handle together with the cylinder 10 is pulled out as far as to the stop and now opens the cock when the segment 30 has been released. In this position the mouth 17 is sufficiently spaced from the rim of the barrel to permit of a convenient dispensing (Fig. 2).

To prevent a filling of liquid through the open cock a light plate valve 53 is guided on the spindle 21' and seals as a check valve at the valve seat 25 of the head 13'. The hollowed out valve hub 54 has in its interior a spring 55, which bears on the one hand on the hub bottom 54 and on the other hand on a spindle collar 56 to urge the valve constantly on its seat. The valve weight and spring are so matched to each other that in position for use, when the spindle is in horizontal position, the spring pressure is just sufficient to close the valve. When the barrel is inclined to dispose the "valve plate above the seat" the valve will always close and will remain closed in the operative position shown in Fig. 2, unless the superatmospheric internal pressure, i.e., the liquid pressure, is sufficient to open the valve. The valve can automatically open only in positions "valve seat over valve plate" but these are positions in which liquid cannot be filled in unless a superatmospheric external pressure is used, which will either endanger the vessel or, as the valve is fairly unstable owing to the spring, the smallest flow can cause the valve to close. The valve is mounted at a low level in the housing so that it is very difficultly accessible through the mouth and the long cylinder and cannot be influenced from the outside. Even if it was possible to reach the valve with any means, the valve might only be pushed to close.

For admitting air, a separate air duct has been provided which is so controlled by a valve and so guided that any interference and soiling is prevented.

From the transverse bore 51 (Fig. 7) of the right-hand claw 9' a bore 58 leads into an annular duct 59 of the screw ring 7 so that it communicates by way of an enlarged portion 60' with a bore 60 which leads into the socket 6. A duct 61 branches from the bore 60 into the oblique socket 62.

This socket 62 has firmly screwed into it an air pressure control valve (Figs. 1, 2, 3), which consists of a screw-threaded socket 64 with neck 64' and housing 63 to which diaphragms 70 are tightly sealed by means of hoops 71 and screws 72 on both sides as in a drum. Seen in the direction of the socket axis 61 the housing ring is provided first (in operative position according to Figs. 1, 2) with a valve seat 63', the valve plate 67 of which with gasket 68 is mounted by means of a spindle 66 guided on transverse arms 65, 65'. To increase the piston effect the diaphragms, which consist preferably of buna, are stiffened with plates 74, which are screwed fast with soldering head screws 75 and collar nuts 76. The collar nuts are engaged by slotted levers 77, which are pivoted by a hinge pin 78 to an offset plate 79 having a neck 80, which is mounted on the spindle 66 and bears on the valve plate the gasket 68 to retain the same. The slotted levers 77 carry thumb levers 81 which bear on the transverse arm 65'. A compression spring 69 which is provided at the spindle end 66 and bears on the transverse arm 65 tends constantly to close the valve. As soon as the pressure in the valve housing exceeds that in the barrel both diaphragms oppose the spring force in the same sense and open the valve.

It is essential to prevent the air conduit from becoming drowned. For this purpose the valve must safely preclude a penetration of liquid. For this reason a trigger 82 (Figs. 1, 2, 3) is provided, which is mounted by means of the shaft 84' in the bearing 83 on the air com-

trol valve in such a manner that the shaft 84' forms a U-shaped rod 84 the limb 84" of which engages a push rod 85, which is pivoted by means of pins 86, e.g., on a bearing bracket 87, to the slide cylinder 13'. An adjusting member, e.g., an adjusting screw 88, enables the trigger 82 to be set so that the valve will be positively sealed when the slide cylinder 10 is pushed in and locked (Fig. 1) whereas in the operative position the trigger 82 lifts from the valve plate so that it does not obstruct the function of the control (Fig. 2).

As the liquid pressure adjacent to the bottom would obstruct the function of the diaphragm-type air valve the neck 64' of the valve housing and with it the linkage 84, 85 must be correspondingly longer in practice than shown in Figs. 1, 2, 3, 4 so that the necessary pressure drop between the diaphragm housing and the surrounding fluid can build up without hindrance and liquid can be discharged at a sufficiently high rate. The dash-and-dot lines 111, 111' (Fig. 2) indicate approximately the path described by the housing 63 of the air control valve during the insertion and removal of the dispensing device (only possible in the dispensing position, Fig. 2).

The barrel can only be filled and cleaned when the dispensing cock has been entirely removed after the removal of the screw ring 7. To prevent this from being done by an unauthorized person the left-hand claw 9 of the screw ring is also bored through and provided with a screw thread 91 (Fig. 7) and a conical groove 109. A screw 93 having a shank 92 could be turned into this bore and the end 90 of this screw could engage a groove 108 (Fig. 8) of the housing flange 5 (Fig. 8). As the flange is held against rotation by the stops 8 of the screw-threaded ring 3 the screw ring 7 cannot be rotated or be turned out until the screw has been screwed back.

The conical groove 109 serves to enable the forcing in of a seal 110 for sealing the closure. The uninjured seal ensures the unfalsified contents of the barrel.

What is claimed is:

1. A liquid container having an opening through which the container can be filled, cleaned and its contents can be dispensed, said container being adapted to assume a dispensing position in which said opening is in the lower part of the container, said container comprising screw means inserted in said opening, and a dispensing device tightly and non-rotatably mounted in said screw means and adapted to be locked and closed and sealed, said dispensing device comprising a housing flange, dispensing means mounted in said housing flange and adapted to be pulled out of said screw means separately of said housing flange, an air inlet device carried by said housing flange and adapted to open responsive to subatmospheric pressure in the container, a separate conduit formed in said housing flange and connected to said air inlet device, said air inlet device having a valve member, said container containing a diaphragm housing containing diaphragm means arranged to control said valve member, said dispensing device comprising a slide cylinder which is adapted to be pulled out and accommodates said dispensing means, and a spring-loaded check valve provided in said slide cylinder on the side thereof facing the container and arranged to open automatically in response to superatmospheric pressure in the container, said check valve being arranged to be inaccessible from the outside.

2. A liquid container as set forth in claim 1, in which said diaphragm means comprise two diaphragms arranged to move in opposite directions under the influence of pressure changes and to undergo a deformation which causes forces to be exerted which are added to each other, said container comprising a linkage operatively connecting said diaphragms to said valve member.

3. A liquid container as set forth in claim 1, in which said slide cylinder is adapted to assume an inner closing position and an extended position and is coupled to said valve member to retain it closed in said locking position and to release it in said extended position.

4. A liquid container as set forth in claim 3, in which said air inlet device comprises a seat and said valve member comprises a plate adapted to cooperate with said seat, and which comprises a linkage connecting said slide cylinder to said plate to urge it against said seat in said locking position and to release it in said extended position.

5. A liquid container as set forth in claim 3, which comprises a spindle, a stirrup member mounting said spindle at the end of said slide cylinder, said check valve being arranged around said spindle, a cock plug rotatably carried by said spindle at the front end thereof in said slide cylinder, an adjusting segment carried by said spindle at the inner end thereof, said cylinder having a cylinder head formed with stops, said segment cooperating with said stops to limit the rotation of said plug and carrying a spring forming a locking pawl, said cylinder head being provided with a rib, said spring and pawl being adapted to cooperate to hold said plug against rotation when said plug is in closed position, a stop provided at said separate conduit and adapted to disengage said spring from said rib responsive to a movement of said slide cylinder to said extended position, said conduit having a recess, said segment being rotatable to engage said recess in order to lock said slide cylinder in said extended position.

6. A liquid container as set forth in claim 5, in which said check valve comprises a valve plate having a hollow hub, one end of which is mounted on said spindle, said spindle carrying a collar mounting the other end of said plug.

7. A liquid container as set forth in claim 5, in which said plug comprises a sealing rim extending beyond the periphery of said slide cylinder, said housing flange being formed with an annular groove, containing a gasket, said screw means consisting of a screw ring retaining said gasket in said groove, said sealing rim being adapted to sealingly engage said gasket in said locking position of said slide cylinder.

8. A liquid container as set forth in claim 5, in which said spindle comprises a spindle head, and which comprises a handle plate arranged before said plug and supported by said spindle head, claws releasably coupling said handle plate to said spindle, a spring cooperating with said handle plate to maintain it coupled to said spindle, said handle plate being axially movable against the force of said spring to uncouple it from said spindle, said handle plate having a surface facing said plug and formed with spiral grooves, bolts pivoted to said plug and carrying pins in engagement with said grooves to rotate said bolts in response to a rotation of said handle plate.

9. A liquid container as set forth in claim 1, in which said screw means consists of a screw ring formed with an annular duct and which comprises a seal bore and a second conduit, said separate and second conduits connecting said annular duct to said seal bore.

10. A liquid container as set forth in claim 9, in which said housing flange comprises a groove and said screw means consists of a screw ring and which comprises a screw screwed into said screw ring and having a shank engaging said groove.
